UNITED STATES PATENT OFFICE.

CHARLES H. DOWNES, OF JERSEY CITY, NEW JERSEY.

STYLOGRAPHIC FOUNTAIN-PEN.

SPECIFICATION forming part of Letters Patent No. 225,810, dated March 23, 1880.

Application filed February 9, 1880.

To all whom it may concern:

Be it known that I, CHARLES H. DOWNES, of Jersey City, in the county of Hudson and State of New Jersey, have invented certain new and valuable Improvements in Stylographic Fountain-Pens; and I do hereby declare that the following is a full, clear, and exact description of the construction and operation of the same, reference being had to the annexed drawings, making a part of this specification, and to the letters and figures of reference marked thereon.

Figure 1 of the drawings is a diametrical section through the lower portion of a stylographic fountain-pen, highly magnified, having my improvements applied to the point-section. Fig. 2 is an enlarged perspective view, in detail, of the threaded notched section and its screw-plug. Fig. 3 is a cross-section 20 taken in the plane indicated by dotted line *x* *x*, Figs. 1.

Similar letters of reference indicate corresponding parts.

This invention relates to writing-instruments known as "stylographic fountain-pens," having a point-section which is removably attached to a hollow handle that serves as a reservoir for writing-fluid.

My invention consists, mainly, in adjustably attaching a notched and screw-threaded tube directly to the interior surface of the point-section and inclosing the upper portion of the needle, also a spring and an adjustable plug, inside of said tube, secure from contact with ink.

The invention also consists in a single independent externally-notched and screw-threaded tube, which is adapted for use inside of and attached directly to the point-section of a stylographic fountain-pen, in combination with a needle, a spring, and a plug for adjusting the tension of this spring and keeping it secure from contact with ink, as will be fully understood from the following description.

In the annexed drawings, A designates a hollow case or handle, which serves as a reservoir for writing-fluid, and which may be constructed in any suitable manner for supplying ink to the point of the pen during the act of writing.

B designates the point-section which is

shown in Fig. 1 screwed into the end of the handle A. This section B is constructed with a tapered writing-point, *a*, which has a fine bore through it, and a durable tip, *e*, of metal 55 or other suitable substance. Inside of the section B is a female thread, *b*, which is designed to receive male threads *c*, that are made in flanges *c'* on the exterior surface of a tubular section, C, between which screw-threaded flanges 60 notches *d* are made, as clearly shown in Figs. 2 and 3. The tube C is endwise adjustable in the point-section B for the purpose of nicely regulating the desired amount of protrusion of the point of a needle, D, beyond the writing-tip *e* and compensating for the wearing away of the needle-point. This adjustment may be easily effected by removing the point-section B from its handle A and inserting the bit of a screw-driver into notches *f* in the upper enlarged end of the tube C. The stem or upper portion of the needle D passes freely through the lower end of the tube C, and has check-collars *g* *g'* on it. Inside of the tube C the needle D is surrounded by a spring, *h*, one 75 end of which bears on the collar *g* and the other end presses against an adjustable screw-plug, *k*, which is tapped inside of the tube C, and preferably notched to receive the bit of a screw-driver, for adjusting it and thereby regulating the tension of the spring *h* on the needle D and keeping the collar *g* down on its seat when pressure is removed from the needle-point.

In practice the lower part of the needle D 85 will be tapered and the bore of the point *a* correspondingly tapered, so that when the needle is on its seat in said bore it will act as a valve and prevent any escape of ink from the point-section.

It will be seen that the small tube C, which serves as a holder for the needle, its spring, and screw-plug, is adjustably attached directly to the inner threaded surface of the point-section B. At the same time provision is made, by 95 means of the notches *d* in the exterior of the tube C, for allowing a free flow of ink past this tube to the point of the pen.

It will also be seen that, notwithstanding tube C is entirely submerged in ink, no ink can 100 enter it to corrode the spring *h* or clog the needle where it passes through this tube.

By removing the point-section B from the handle A the reservoir in the latter can be supplied with ink.

In this application I do not claim the subject-matters embraced in three interferences, in which a former application of mine, filed September 12, 1879, has been placed, said subject-matters being as follows: The combination, with the handle or pen-case of a fountain-pen, of the needle holding and supporting tube attached to and supported by the walls of said handle or case; in a fountain-pen, the combination, with a sectional handle, of the needle holding and supporting tube inserted and secured in the lower section; in a fountain-pen, a spindle-holder adjustably held at the lower end of the ink-reservoir in a fixed part of the outer case; in combination with the needle-carrying tube, the needle-valve fitting loosely within said tube and provided with a stop to limit its backward movement.

Having described my invention, I claim—

1. In a stylographic fountain-pen having a section, B, which is provided with an internal screw-thread, a threaded notched section, C, 25 adjustable therein, as described.

2. The screw-threaded notched section C, arranged within the section B, and carrying within it a spring, a needle, and a screw-plug for adjusting the same, substantially as herein 30 set forth.

3. For a stylographic fountain-pen, an independent section, C, formed with a scalloped or notched exterior surface, which is provided with a screw-thread, and which carries a needle, a plug, and a spring, the spring so enclosed as to be secure from contact with ink, 35 substantially as herein set forth.

CHARLES H. DOWNES.
